UNITED STATES PATENT OFFICE.

FRANK CORTESE, OF CHICAGO, ILLINOIS.

COMBINED SUPPORTING AND ELEVATING DEVICE FOR EMBLEMS.

1,334,890.

Specification of Letters Patent. Patented Mar. 23, 1920.

Application filed April 13, 1918. Serial No. 228,488.

To all whom it may concern:

Be it known that I, FRANK CORTESE, a citizen of the United States, residing at Chicago, in the county of Cook and State 5 of Illinois, have invented new and useful Improvements in Combined Supporting and Elevating Devices for Emblems, of which the following is a specification.

This invention relates to a device which 10 may be advantageously employed to elevate and support in an elevated position an emblem such as a flag or the like.

The primary object of the invention is to provide a simple and inexpensive device 15 of this character wherein a pole has fixed to the top thereof a sprocket wheel holder of novel construction.

With these and other objects in view the invention resides in the novel combination 20 and arrangement of parts which will be hereinafter described and claimed.

In the drawing:—

Figure 1 is a view in side elevation of a combined supporting and elevating device 25 for emblems constructed in accordance with the invention.

Fig. 2 is a vertical longitudinal section upon an enlarged scale through the upper end of the pole and the sprocket wheel holder which is mounted thereon.

Fig. 3 is a detailed perspective view of the sprocket wheel holder.

Fig. 4 is an enlarged detailed sectional view on the line 4—4 of Fig. 1.

Like characters of reference denote corresponding parts throughout the various views in the drawing.

Referring now to the drawing in detail the letter A designates a combined supporting and elevating device with which is 40 shown connected an emblem B.

The device A includes a pole 5 which is adapted to be mounted upon a support in any suitable manner and has secured there- 45 to adjacent its base a housing 6. A sprocket wheel 7 is arranged within the housing 6 and fixed to a shaft 8 which extends exteriorly of the housing and may be engaged by a crank 9 when it is desired to turn the wheel 7 for a purpose which will herein- 50 after appear.

Attached to the pole 5 at its top is a sprocket wheel holder 10 which comprises a circular cap 11 having a convexed top and

a flat bottom face 12 which is adapted to 55 contact with the top of the pole 5. The cap 11 is adapted to protect the top of the pole 5 from the weather and has extending downwardly from its bottom 12 an attaching arm 13 which is driven into the pole and 60 has extending transversely thereof adjacent its pointed end an opening 14. To more firmly secure the arm 13 in the pole 5 a bolt 15 is passed through the pole and the opening 65 in the arm 13.

Extending upwardly from the peripheral edge of the cap 11 is a second arm 16 which terminates at its upper end in a horizontally extending and interiorly threaded sleeve 17. A bolt 18 has its shank passed through the 70 sleeve 17 and serves as a trunnion on which is mounted to turn a sprocket wheel 19. The sprocket wheel 19 is retained upon the shank of the bolt 18 by a washer and a screw 20, the latter of which is removably 75 mounted in one end of the bolt.

A chain 21 is trained over the sprocket wheels 7 and 19 and has each end thereof provided with an eye 22 through which may be passed the bill on a snap hook 23 se- 80 cured in a corner of the emblem B.

From the foregoing description taken in connection with the accompanying drawing it is apparent that when it is desired to elevate or lower the emblem B the sprocket 85 wheel 7 may be rotated through the operation of the crank 9 to cause the chain 21 to travel over the sprocket wheels 7 and 19 in the desired direction.

Having thus described the invention what 90 is claimed as new is:—

In a support for sprocket wheels, a cap having a central downwardly extending arm integrally formed therewith, and said arm having a transverse opening there- 95 through, said cap having at one of its ends an upwardly extending arm terminating in a laterally extending sleeve, and the said sleeve having its bore threaded, and a threaded element providing an axle for a 100 sprocket wheel engaging the threads of said bore and having a non-threaded surface extending outwardly therefrom on which the sprocket wheel is journaled, and means for retaining the sprocket wheel against lateral 105 movement on its shaft.

In testimony whereof I affix my signature.

FRANK CORTESE.
